UNITED STATES PATENT OFFICE.

ANTHONY L. ASTE, OF BROOKLYN, NEW YORK.

SHOE-POLISHING STAND.

Application filed May 10, 1919. Serial No. 296,204.

To all whom it may concern:

Be it known that I, ANTHONY L. ASTE, a citizen of the United States, and a resident of the borough of Brooklyn, county of Kings, 5 city and State of New York, have invented certain new and useful Improvements in Shoe-Polishing Stands, of which the following is a specification.

This invention relates to shoe polishing stands and broadly considered, comprehends a stand of such construction that the foot rest may be disposed out of the way after polishing the shoes so that a person may not be tripped thereby or the skirt or other parts 15 of the clothing torn.

It is one of the important objects of my invention to provide certain improvements which may be embodied in the multiple type of stand construction such as is generally 20 employed in shoe shining parlors and wherein the shoe polishing materials and the foot rest when not in use will be entirely enclosed within the base portion of the stand which will present a flat unobstructed top 25 surface affording a step from which to descend after the shoes have been polished.

It is an additional object of the invention to provide main and supplementary foot rests, the main foot rest being fixed upon a 30 suitable base, and the supplementary foot rest having means to coact with means on the main foot rest to thereby detachably hold the supplementary foot rest in superposed relation to the main foot rest.

35 It is a further detail object of my invention to provide an improved mounting and arrangement of a guide rod for the shoe polishing cloth upon the foot rest base so that the cloth will be guided over the different 40 portions of the shoe as it is drawn around the rod in the polishing operation.

It is a further general object of my invention to provide a shoe polishing stand having the improved features above noted, which 45 is of relatively simple construction, highly convenient and serviceable in practical use and capable of manufacture at relatively small cost.

Having the aforementioned objects in 50 view, the present invention comprehends certain novel and improved combinations of mechanical elements, and the structural characteristics thereof, as will be more fully developed in the following description and 55 subsequently incorporated in the subjoined claims.

Figure 1 is a perspective view of an individual shoe polishing stand or box;

Figure 2 is an enlarged perspective view of the shoe rest base showing the supplementary shoe rest in position;

Figure 3 is a detail transverse section taken on the line 3—3 of Figure 2;

Figure 4 is a top plan view illustrating a slightly modified form of the device;

Figure 5 is a similar view showing the modified construction of the supplementary foot rest for use in conjunction with the main foot rest seen in Figure 4;

Figure 6 is a detail section taken on the 70 line 6—6 of Figure 4 with the supplementary foot rest in position; and

Figure 7 is a perspective view illustrating one embodiment of the invention as applied to a multiple type of shoe polishing stand. 75

Referring in detail to the drawings, and more particularly to Figures 1, 2 and 3 thereof, 5 designates a box or receptacle of suitable dimensions, which, as herein shown, is preferably of rectangular form and is supported at its corners by the legs 6. The interior of the box or receptacle 5 is divided by a vertical partition 7, into two compartments, in one of which the brushes and polishing cloths may be placed while the other 80 receives the boxes and bottles of shoe polish.

The top of each compartment of the box is closed by means of a cover. These covers, designated 8 and 9 respectively, are hinged to the opposite longitudinal edges of a transverse bar 10 as shown at 11, said bar being 90 suitably fixed to the upper edges of the side walls of the box 5.

Upon the under side of the cover 8, a base block 12 is secured, said block being 95 of less length and width than the cover 8. Upon the block 12, a metal plate 13 is securely fixed, and upon the surface of this plate at its opposite longitudinal edges and in spaced relation to each end thereof, the 100 guide lugs 14 are formed. The inner faces of these guide lugs are beveled or inclined as seen at 15 for a purpose to be presently referred to. It is to be observed that the plate 13 is of wedge shaped form, or gradually tapers in width from one of its ends to the other. In the end face of the base block 12 and spaced from the wider end of the plate 13, a metal plate 16 is countersunk and securely fixed to the base block. The 110 upper edge of this plate projects slightly above the upper surface of the block 12 for

105

a distance substantially equal to the thickness of the plate 13. This plate 16 affords a step against which the heel of the shoe abuts when the foot is placed upon the plate 13. In such case, the edges of the shoe sole fit between the lugs 14 on the longitudinal edges of said plate.

In the use of the device for polishing ladies' shoes, it is hardly possible that the shoe will properly fit between the lugs 14 on the shoe rest plate 13. I have therefore provided a supplementary foot rest 17 in which the plate 18 conforming to the outline of the foot is connected by means of the standards 19 to a wedge shaped plate 20, the longitudinal edges of which are beveled as at 21. The plate 18 is of the usual form now in general use and is provided with a transverse shoulder 22 against which the heel of the shoe abuts. In the application of this supplementary foot rest, it is moved longitudinally upon the surface of the plate 13 in a forward direction until its beveled edges 21 are frictionally engaged with the beveled faces 15 of the lugs 14. As the pressure upon the plate 18 exerted by the foot is in a forward direction, the supplementary foot rest will thus be securely held against shifting movement and retained in superposed relation to the main foot rest plate 13.

In order to facilitate the polishing of the shoe, a wire rod 23 is provided as a guide for the polishing cloth. This wire rod is bent to provide the side portions 24 extending longitudinally in diverging relation to the side faces of the block 12 in a rearward direction. The transverse connecting portion 25 at the forward ends of the side portions 24 of said rod is seated in a groove or channel 26 formed in the end face of the block 12. The side portions 24 of the rod at their rear ends are angularly bent in an inward direction as at 27 and securely fixed in any suitable manner in the base block. The polishing cloth is disposed upon the shoe in the usual manner and the ends of the cloth passed downwardly between the sides of the block 12 and the diverging portions 24 of the wire rod. These ends of the cloth are tightly grasped in the hands and pulled around the rod, being moved alternately in opposite vertical directions. As the cloth is thus drawn across the surface of the shoe, the latter is polished and by contact with the diverging portions 24 of the wire rod, the cloth also shifts longitudinally upon the surface of the shoe and in a forward direction. Thus the frictional contact of the cloth upon the shoe surface, is evenly distributed so that a high polish may be quickly obtained.

After the device has been used, the cover 8 is swung over to its closed position and the shoe rest and other parts on the base block 12 enclosed within one of the cham-

bers of the box or receptacle 5. It will therefore be apparent that in descending from a chair, the foot may be placed upon the closed top of the box which serves as a step. It is not an uncommon occurrence in 70 polishing stands where the foot rests are stationary for ladies' skirts to be caught in the foot rest and badly torn and also with the possibility of the wearer being tripped and severely injured. With my improved construction, as all of the parts are entirely out of the way and enclosed within the body of the box or stand, this could not possibly occur.

In Figures 4, 5 and 6 of the drawings, I 80 have disclosed a slightly modified embodiment of the double foot rest, wherein the main foot rest 28 which is fixed upon the base block, is also in the general outline form of a shoe. The side edges of this main 85 foot plate at the opposite ends thereof are beveled as at 29. The base plate 30 of the supplementary foot rest is of wedge shaped form and is provided upon its side edges and at its opposite ends with the inwardly 90 inclined flanges 31. In this case, the front ends of the main foot rest and of the base plate of the supplementary foot rest are relatively wide, said plates tapering to their rear ends which is the reverse of the construction first referred to. The supplementary foot rest is however applied to the main foot rest in a similar manner and is moved from the rear of the main foot rest towards the front thereof until the flanges 100 31 come into frictional binding engagement with the inclined or beveled faces 29 of the foot plate 28. In either case, it will be apparent that the supplementary foot rest may be very easily and quickly applied to or 105 removed from its operative position in superposed relation to the main foot rest. When removed, the supplementary foot rest can be conveniently housed within one of the compartments of the box or the receptacle. 110

In Figure 7 of the drawings I have disclosed an embodiment of my invention as applied to the multiple type of shoe polishing stand such as is generally seen in shoe polishing parlors. In this construction, the base portion 32 of the stand is divided by a series of vertical partitions 33 forming a plurality of compartments which are adapted to be closed by the hinged cover members 34 as in the individual type of the stand above described. In this instance however, the cover members when closed are supported by longitudinal cleats indicated at 35, which are secured to the front and rear walls of the base portion 32. Thus these cover members when closed will have their upper surfaces flush with the upper edge of the front wall of the base portion 32. I have shown a foot rest 36 of conventional type secured to the base block, carried by the 130

cover member 34 which is also provided with the guide rod for the polishing cloth before referred to. It will however be understood that the cover member may be 5 equipped with either of the two forms of foot rests which I have previously described so that a supplementary foot rest can be employed. In the adaptation of my invention to the multiple type of polishing stand, 10 the foot rest may be applied only to alternate cover members or to all of said cover members as may be desired. When these cover members are all arranged in closed position, the base portion 32 of the stand 15 has a perfectly flat and unobstructed top so that persons descending from the platform 37 may step thereon and from said base portion to the floor. Accordingly, it is not necessary for ladies to observe extraordinary caution in descending from the stand 20 or to lift the skirts in order to escape the foot rests or prevent soiling by contact with the polishing paste or other materials.

From the foregoing description, considered in connection with the accompanying drawings, the construction, manner of use and several advantages of my improved shoe 25 polishing stand will be clearly and fully understood. The several improvements are 30 of a simple character and may be embodied either in the individual or multiple type of stand at relatively small cost. By the provision of the detachable supplementary foot rest, the utility of such stands is materially 35 enhanced and the guide rod for the polishing cloth provides means which will enable the shoes to be speedily and satisfactorily polished.

In the preceding description and the accompanying drawings I have disclosed practical embodiments of the invention, which, 40 however, may likewise be exemplified in numerous alternative constructions. Accordingly the invention as herein claimed is to 45 be considered as inclusive of all legitimate equivalents for the various elements em-

ployed as well as other contemplated arrangements thereof, which may satisfactorily accomplish the desired results.

I claim:

1. A shoe polishing stand comprising a base provided with compartments therewithin, doors closing the tops of the compartments, shoe receiving means carried by the underfaces of said doors, said doors being hinged 55 to swing alternately one over upon the other whereby to expose successively the right and left shoe receiving means, said doors each swinging upon a line extending forwardly from the seat occupied by the patron. 60

2. In a shoe polishing stand, the combination of a platform, a base extending in stepped relation to the platform and provided with a series of pairs of compartments therein, seats on the platform, pairs of 65 doors hinged at their adjacent edges on a line substantially transverse to the platform and base and extending outwardly from the intermediate portion of the respective seats, said doors adapted to swing the one upon 70 another when in open position, and shoe receiving means held by the underfaces of said doors and adapted to be exposed for use when the doors are opened.

3. In a shoe polishing stand, the combination of a platform, seats thereon, a base, supports on the base forming an unobstructive step to the stand, wedge receiving means on said supports, and shoe rests also carrying co-operating wedge means 75 slidable 80 longitudinally of the foot rests into the first wedge receiving means in a direction away from the platform to secure the foot rests in interlocking engagement therewith, said foot rests adapted to be held in interlocking engagement by the thrust of the foot 85 of a patron occupying a seat.

In testimony that he claims the foregoing as his invention he has signed his name hereunder.

ANTHONY L. ASTE.
